APPARATUS FOR INSERTING FILLING
YARNS IN CIRCULAR LOOMS

Juan Puigcorbé Marín, Barcelona, Spain

Application January 22, 1952, Serial No. 267,597

3 Claims. (Cl. 139—16)

1

This invention relates to circular weaving looms and has particular relation to a new and improved mechanism for inserting filling yarns in circular looms.

It is an object of the invention to provide a circular loom having mechanism for inserting filling yarns, which is characterized by a plurality of shuttles operating simultaneously and successively, so that the productive capacity of the loom is increased considerably.

Another object of the invention is the provision of a circular loom of the character described which affords efficiency and dependability of operation to a degree heretofore unobtainable in looms of this type.

The mechanism consists of a circular operating device which transmits a rotary motion to a plurality of satellite pinions located peripherally and distributed uniformly around said device, which pinions transmit the movement received from said driving device to arcuate shuttles which carry one or more bobbins and are guided in a circular path around the operating device when the pinions are rotated, passing through the sheds formed at the proper time in each of the multiple sections into which the warp of the loom is annularly divided.

The circular operating device which transmits the general motion to the rotary pinions may be a gear or crown gear, a chain, a perforated belt or the like.

Other objects and advantages of the invention will be apparent in the course of the following specification when taken in connection with the accompanying drawings which illustrate a preferred embodiment by way of illustration only and not in a limiting sense.

Fig. 1 is a plan view partially in section, of a portion of a loom showing one of the shuttles and the mechanism for driving the shuttle.

Fig. 2 is a vertical section taken substantially along line 2—2 of Fig. 1.

Fig. 3 is a perspective view of the shuttle and mechanism of Figs. 1 and 2, as seen from the outside of the loom, with portions broken away to reveal internal construction.

The mechanism includes an annular rack 1 having a continuous row of teeth 2 around its inner periphery. These teeth 2 mesh with the teeth of one or more pinions, such as the pinion 3 which is mounted on a shaft 4. The shaft 4 is rotated by suitable driving mechanism (not shown) of the machine whereby the pinion 3 rotates the rack 1. In rotating, the rack 1 rests upon a fixed circular support 5 which has a

2

plurality of spaced, upstanding, circular guide rails 7 which interfit with corresponding depending circular guide rails 8 of the rack 1, for guiding said rack 1 for rotation in a circular path. The support 5 is immovable, being secured by keying 6 to a fixed central column 11 which is rigid with the machine frame.

The rack 1 is provided with a continuous row of teeth 12 around its outer periphery which meshes with the teeth of a plurality of satellite pinions 13 for uniform rotation of said pinions 13 when the rack is rotated. The pinions 13 are spaced from each other, and each is supported by a depending pivot 14 which is mounted in a vertical bearing 15.

The pinions 13 engage with the teeth 18 of flat arcuate shuttles 16 which are spaced radially from the outer periphery of the rack 1, as shown in Fig. 3. The shuttles 16 have opposed pointed ends 17 which perform the shuttle operation. Each shuttle 16 has an arcuate guide rail 19 on its top and bottom surface, which guide rails are aligned and positioned to fit within corresponding arcuate grooves formed in respective spaced support blocks 22 and 23. The support blocks 22 are integral with an angular annular member 20 and extend radially therefrom, while the blocks 23 are integral with a similar angular annular member 21, and extend radially from said annular member 20. The annular members 20 and 21 are rigidly fixed to respective supports 5 and 9 as by means of screws 24 and 25. The support 9 is in turn rigidly and immovably mounted on the central column 11 as by keying 10. Each lower block 22 supports the bearing 15 of one of the pinions 13. Each pinion 13 is thus rotatably mounted between a pair of vertically aligned blocks 22 and 23.

Each shuttle 16 carries one or more bobbins, such as the bobbin 26, which depends therefrom and is so inclined that its longitudinal axis coincides with the axis of the shed formed in the warp yarns *a* and *b*. When a shuttle is provided with more than one bobbin, the end of the yarn of one bobbin must be connected to the beginning of the yarn wound on the next bobbin. As the yarn 27 is unwound from bobbin 26, it is conducted through a yarn guide 28 to its point of insertion 29 from which it is inserted between the angle of the shed formed between the yarns *a* and *b*.

In order to allow the insertion of the filling yarns, the shed must be opened by a suitable set of heddles which are not shown, but whose manner of operation and location at or near

the top of the machine will be familiar to those skilled in the art. Upon the formation of the shed some of the warp yarns *b* must be suitably held by their heddles in a vertical position between the outer peripheral edges of the fixed annular members 20 and 21 and the inner toothed edge of the shuttles 16, as shown in the drawings. The remaining warp yarns *a* are held by their corresponding heddles inclined outwardly beyond the outer arcuate edges of the shuttles 16. The warp yarns *b* in the vicinity of each of the revolving shuttles 16, are located within the spaces between the pairs of alined blocks 22 and 23, as clearly shown in Figs. 1 and 3, so that they are divided into annular sections spaced by said pairs of blocks 22 and 23, in order to permit the traversal of the shuttles 16 in mesh with the pinions 13.

After a particular shuttle 16 has passed a pinion 13 and left its filling 27, the shed behind this pinion 13 is momentarily left free and unobstructed until the arrival of the next shuttle. During this time, the warp yarns are recrossed by their heddles to form a new shed, so that all or part of the yarns *a* take the position formerly occupied by yarns *b* and all or part of the yarns *b* take the position formerly occupied by yarns *a*. An unobstructed path through the newly-formed shed is thus provided by the heddles for the next approaching shuttle 16.

As can be noted from the drawings, the pinions 13 are spaced apart a sufficiently close distance to enable each shuttle 16 to be in constant mesh with at least two of the pinions 13, so that each shuttle is also always guided by at least two pairs of alined support blocks 22 and 23.

Since a considerable number of shuttles 16 may be provided to operate simultaneously in a single machine, it is possible to increase the productive capacity of a loom to a substantial extent.

While a preferred embodiment of the invention has been shown and described herein, it is obvious that numerous changes, omissions, and additions may be made without departing from the spirit and scope thereof. For example, instead of the guide rails 19, any suitable equivalent guide means may be used to guide the shuttle in a circular path. Again the transmission of motion from the pinions 13 to the shuttles 16 can be effected by the engagement of the teeth of said pinions with teeth arranged on any suitable portion of said shuttles.

What is claimed is:

1. In a circular loom which has a frame and movable heddles for forming sheds in warp yarns carried by said frame, a mechanism for inserting filler yarns in said sheds, said mechanism

comprising a circular rack extending entirely around said frame and having teeth on the outer rim thereof, and mounted for rotary movement relative to said frame, drive means located centrally in said frame for rotating said rack, said frame having radial extensions extending outwardly of said rack and divided into vertically aligned and spaced pairs, said pairs of frame extensions being circumferentially spaced around said frame, a pinion mounted between each said pair of frame extensions and meshing with the teeth of said rack, said frame extensions having track means therein outwardly of said pinions, a shuttle mounted in said track means for movement about the circumference of said rack between the pairs of frame extensions, said shuttle having inner teeth which mesh with the teeth of said pinions, and a bobbin for filler yarns carried by said shuttle, whereby said shuttle is adapted to be driven around the circumference of said rack to lay a filler yarn within said sheds.

2. A mechanism in accordance with claim 1 in which the warp yarns comprising said shed are divided into an inner group and an outer group, said inner group being located between said circular rack and the path of said shuttle and being divided annularly by said frame extensions, said outer group being located outwardly of the path of said shuttle and also outwardly of said frame extensions, said bobbin depending substantially vertically from said shuttle, said shuttle also carrying thread guiding means having an outlet opening adjacent the bottom of said shed, whereby a filler thread carried by said bobbin is adapted to be drawn through said outlet opening and laid substantially at the bottom of said shed upon movement of said shuttle.

3. A mechanism in accordance with claim 2, in which said thread guiding means has an outlet portion in which said outlet opening is located, said outlet portion being thin and flat, whereby it is adapted to fit slidably in the bottom of said shed.
